Primary Examiner — Martie K Holtje*(74) Attorney, Agent, or Firm* — Winston & Strawn LLP(57) **CLAIM**

The ornamental design for a watch face, as shown and described.

DESCRIPTION

FIG. 1 is a front elevational view of a first embodiment of a watch face showing our new design;

FIG. 2 is a front perspective view of FIG. 1;

FIG. 3 is a front elevational view of a second embodiment of our design of FIG. 1;

FIG. 4 is a perspective view of FIG. 3;

FIG. 5 is a front elevational view of a third embodiment of our design of FIG. 1;

FIG. 6 is a perspective view of FIG. 5;

FIG. 7 is a front elevational view of a fourth embodiment of our design of FIG. 1;

FIG. 8 is a perspective view of FIG. 7;

FIG. 9 is a front elevational view of a fifth embodiment of our design of FIG. 1;

FIG. 10 is a perspective view of FIG. 9;

FIG. 11 is a front elevational view of a sixth embodiment of our design of FIG. 1; and,

FIG. 12 is a perspective view of FIG. 11.

The structural features depicted by broken lines in the drawings have been shown for the purpose of illustrating environment that forms no part of the claimed design.
